UNITED STATES PATENT OFFICE.

MADISON F. HODGE, OF LEAVENWORTH, KANSAS, ASSIGNOR OF ONE-HALF
TO HERBERT W. WOLCOTT, OF LEAVENWORTH, KANSAS.

TROLLEY-RETRIEVER.

No. 853,453.

Specification of Letters Patent.

Patented May 14, 1907.

Application filed December 18, 1905. Serial No. 292,366.

To all whom it may concern:

Be it known that I, MADISON F. HODGE, a citizen of the United States, residing at 1200 South Second street, Leavenworth city, in the county of Leavenworth and State of Kansas, have invented certain new and useful Improvements in Trolley-Retrievers, of which the following is a specification.

My invention relates to trolley retrievers of that character which automatically cuts short the upward spring of the trolley when it leaves the wire and instantly draws it downward to a position below the wire, and my object is to produce an efficient and reliable device of this character and one which can be reset with convenience and despatch.

With this general object in view and others as hereinafter appear, the invention consists in certain novel and peculiar features of construction and combinations of parts as hereinafter described and claimed; and in order that it may be fully understood reference is to be had to the accompanying drawings, in which—

Figure 1, indicates a top plan view of a trolley retriever embodying my invention, the casing or housing being omitted. Fig. 2, indicates a vertical section taken on the line II—IV of Fig. 1, in the direction indicated by the arrow, with a part broken away. Fig. 3, is a vertical section taken on the line III—III of Fig. 1. Fig. 4, is a section taken on the line II—IV of Fig. 1 but viewed in the opposite direction from that indicated by the arrow.

In said drawings, 1 indicates the front plate 2 the sides and 3 the substantially U-shaped body of a housing, said body being secured at its side margins in any suitable manner to sides 2, and at its ends to the plate 1, and said housing is provided in its upper side with a transverse slot 4, and with a longitudinal slot 5.

6 indicates a shaft journaled in the sides 2 of the housing and 7 a collar rigid on said shaft and engaging externally one of the sides 2. The adjacent end of the shaft is preferably squared as at 8 to receive the handle 9, for a purpose hereinafter explained.

Within the housing the shaft is provided with a threaded portion 10 and at one end

of said threaded portion a ratchet wheel is mounted on said shaft. The toothed portion 12 of the ratchet wheel is disposed at 55 the inner end of the hub so as to provide a chamber into which projects pins 13 from the adjacent side of the housing, said pins being disposed circularly so as to confine between them the main spring 14, secured 60 at its inner end as at 15 to the hub of the ratchet wheel and at its outer end as at 16 to a bolt 17, the inner end of said bolt being secured to an internal arm 18, of the housing. The screw 15 for securing the spring 14 to 65 the ratchet wheel may, if desired, be utilized for securing said wheel rigidly on the shaft, as shown in Fig. 3, said wheel and collar 7 engaging opposite sides of the contiguous side of the casing to prevent endwise movement of the shaft.

Pivoted on bolt 17 is a pawl 19 having recesses 20 in its upper side, said recesses being at opposite sides of its pivotal point.

21 is a catch having an opening 22 engaged 75 slidingly by a spring 23 overlying the pawl and the toothed portion of the ratchet wheel and secured at one extremity as at 24 to plate 1, the tendency of said spring being to hold the catch pressed yieldingly against the 80 pawl so as to hold the latter in engagement with or away from the ratchet. The catch projects up through opening 5 of the housing so that the conductor can readily grasp and move the same, the elongated form of the 85 opening permitting the catch to be adjusted for engagement with one of the recesses 20 of the pawl or the other.

When the device is in operative position the catch is in engagement with the recess at 90 the toothed end of the pawl as shown in full lines Fig. 4. When the retriever is to be reset the catch may be moved to the position shown in dotted lines same figure.

Secured to or formed integral with the 95 ratchet wheel as shown, is a clutch member consisting of a collar 25 having a lug 26 projecting from its inner face and provided at its front end with a groove 27. If desired the part 26 may be an integral projection from 100 the ratchet wheel instead of from the collar, as shown.

28 indicates a reel journaled on shaft 6, at the opposite end of the grooved portion 10

thereof from the ratchet wheel, and 29 the trolley rope, the same being secured at its inner end to the reel as shown or in any other suitable manner, and extending thence up 5 through the slot 4 of the housing to the trolley pole not shown, the rope being kept taut by a spring 30, secured at its inner end as at 31 to the hub of the reel, and at its outer end to one of a series of pins 32 surrounding the 10 spring and rigid with the contiguous side of the housing.

A clutch member made rigid with the reel in any suitable manner preferably consists of a disk or collar 33, having a lug 34 projecting from its face toward the ratchet wheel, one end of the lug being grooved as at 35 so that at the proper time the tongues produced by grooving lugs 26 and 34 shall interlock with each other as hereinafter described. The 15 disk 33 is also provided with a radial passage 36 communicating at its inner end with the groove of the thread 10.

Pivoted on the reel as at 37 at diametrically opposite points are a pair of swing arms 25 38, terminating at diametrically opposite points in enlarged ends or weights 39 and one of said swing arms is provided at the opposite side of its pivotal point with an arm 40 pivotally connected by link 41 with the companion 30 arm 38, and rigid with said link and projecting inwardly therefrom through passage 36 is a dog 42, having its inner end preferably pointed slightly projecting into the vertical plane of the groove of the thread 10; said dog 35 normally occupying the position shown in Fig. 2 in order that slight lateral movement of the pawl will dispose its end in the groove of the thread 10 and thus, as hereinafter explained, cause the reel to travel on the shaft 40 until its clutch member engages with the clutch member of the ratchet wheel.

To hold the dog 42 normally out of engagement with the groove of the thread, a spring 43 presses at its free end against the periphery of disk or collar 33 and is secured at its 45 opposite end by set screw 44, to one of the swing arms 38, preferably the one which is not provided with the arm 40.

When the device is in operative position, 50 the parts are all arranged as shown in full lines except pawl 19, so that if the trolley wheel leaves the wire its incidental upward spring, through the movement of the trolley rope will instantly revolve the reel in opposition to spring 30. Immediately this action begins the arms 38 swing outward by centrifugal force in opposition to spring 43 and cause the dog to move radially into engagement with the groove of the thread 10, and 55 60 thereby compel the reel to move spirally toward the ratchet wheel, the spring 30 yielding sufficiently to permit this action to take place, which in practice is almost instantaneous with the disengagement of the trolley rope 65 from the wire. As the clutch lug 34 im-

pinges upon and interlocks with the clutch lug 26 the ratchet wheel is caused by said impact to move very slightly in the direction indicated by the arrow Fig. 4, this movement being sufficient to permit the spring 23 to 70 trip the pawl 19 from engagement with said ratchet wheel, which action in turn is instantly followed by the reverse operation of said ratchet wheel under the power of its spring 14, and in this connection it will be 75 noticed that the spring 30 co-operates with spring 14 in reversing the rotation of the ratchet wheel and the reel, though the principal function of the spring 30 as hereinbefore stated is to keep the rope taut that it 80 may start the reel action instantly and thus insure an almost instantaneous checking and depression of the trolley after it leaves the wire. The power of the spring 14 is great enough to rewind sufficient rope on the reel 85 to draw the trolley wheel down below the plane of the supports of the trolley wire and in practice the action is so quick that such result is accomplished by the time the car has traveled twice its length. To reset the 90 trolley the catch is then slipped forward to force the pawl into engagement with and lock the wheel against back rotation and then the conductor grasps the rope above the retriever and pulls upward upon it, this action 95 through the engagement of the clutch members rewinding the spring 14 and spring 30. Because of the fact that the pawl 19 snaps into engagement with the teeth of the ratchet wheel successively, the conductor is 100 enabled to reset the retriever by a succession of pulls or jerks on the rope and can therefore reset it without difficulty because he is enabled to brace himself by placing one hand or arm against the car. 105

As soon as the trolley is reset the pull on the rope is relaxed and the slack in the same permits the spring 30 to turn the reel and take up such slack, the incidental back revolution of the reel through the engagement of 110 its dog with the groove of the thread 10 returning the reel to its original position. As its movement ceases the dog is withdrawn from the groove. The operator then slides catch 21 to the position shown by dotted 115 lines, the pressure of the ratchet wheel against the end of the dog holding the latter in operative position and ready to fly upward as soon as the ratchet wheel starts to move in the direction indicated by the arrow 120 Fig. 4.

It will be noticed that the movement of the reel toward the ratchet wheel is always opposed and cushioned by the spring 14, and that the action of said spring co-operates in 125 forcing the reel back to its original position after the wheel has been reset and it will be further noticed that the stepped or grooved form of the clutch faces of the clutch lugs tends to eliminate the tendency of the reel to 130

recoil when the shock of contact is opposed by the power of the spring 14. For the convenience of some conductors who may find difficulty in resetting the retriever by means 5 of the rope, I have provided the handle 9, which gives the conductor greater leverage over the spring 14 than he obtains through the medium of the rope. The resetting operation by means of the rope is preferable 10 to because it can be effected with greater celerity than by means of the handle.

All succeeding operations are repetitions of those above described.

If the spring 14 should break the ratchet 15 wheel can be locked by pawl 19, and the spring 30, will prevent the trolley going up too high. The device acts as a catch in this case but not as a retriever.

From the above description it will be apparent 20 that I have produced a trolley retriever possessing the features of advantage enumerated as desirable in the statement of invention and which obviously may be modified in its form, proportion, detail construction 25 and arrangement of the parts without departing from the principle of construction involved.

Having thus described the invention what I claim as new and desire to secure by Letters Patent, is:—

1. A trolley retriever, comprising a housing, a shaft journaled in the housing and provided with a screw-thread, a wheel rigid on the shaft, a reel journaled on the shaft and engaging said wheel, a trolley rope upon and secured to the reel and extending through the housing, means for yieldingly resisting rotative movement of the wheel imparted by a pull on said rope, means to lock the wheel 40 against back rotation when the pull on the rope ceases, means to then revolve the reel in the opposite direction, and a dog rotatable with the reel and adapted during the back rotation of the latter to engage said screw-thread.

2. A trolley retriever, comprising a housing, a shaft journaled in the housing, a wheel rigid on the shaft, a reel journaled on the shaft and engaging said wheel, a trolley rope 50 upon and secured to the reel and extending through the housing, means for yieldingly resisting rotative movement of the wheel imparted by a pull on said rope, means to lock the wheel against back rotation when the pull on the rope ceases, means to then revolve the reel in the opposite direction, a screw-thread, a dog in engagement with said thread when the reel is revolving; one of said last-named elements revolving with the reel 55 to cause it to move away from the wheel during such back revolution, and means to effect disengagement between the dog and screw thread when the rotation of the reel ceases.

3. A trolley retriever, comprising a housing, a shaft journaled therein and provided

with a screw-thread, a wheel rigid on the shaft and provided with a clutch member, a reel journaled on the shaft and provided with a companion clutch member, and a dog carried by the reel and adapted to engage the 70 screw thread when the reel is rotating and cause it to move toward the wheel until the clutch members engage or from the wheel until the clutch members are disengaged.

4. A trolley retriever, comprising a housing, a shaft journaled therein and provided with a screw-thread, a wheel rigid on the shaft and provided with a clutch member, a reel journaled on the shaft and provided with a companion clutch member, a dog rotatable 80 with the reel, and means carried by the latter and adapted to move outward under centrifugal force when the reel is rotating, and force the dog into engagement with the thread.

5. The combination of a housing having 85 an opening, a shaft carried by the housing and provided with a screw-thread, a reel journaled on the shaft and provided with a clutch member, a dog rotatably movable with the reel and adapted to engage the screw 90 thread when the reel is rotated and move the latter longitudinally on the shaft, and a second clutch member to be engaged by and arrest the movement of the first-named clutch member and the reel carrying the same. 95

6. The combination of a housing having an opening, a shaft carried by the housing, and provided with a screw-thread, a reel journaled on the shaft and provided with a clutch member, a swing arm pivoted to the 100 reel, a dog connected to said swing arm and held yieldingly out of engagement with the screw-thread when the reel is at rest and adapted when the reel is rotating to be moved by the swing arm into engagement 105 with the screw thread and effect longitudinal movement of the reel on the shaft, and a second clutch member to be engaged by and arrest the movement of the first-named clutch member and the reel carrying the same. 110

7. A trolley retriever, comprising a housing, a shaft journaled therein and provided with a screw thread, a wheel rigid on the shaft and provided with a clutch member, a reel journaled on the shaft and provided with 115 a companion clutch member, a swing arm pivoted to the reel, and a dog connected to said swing arm and held yieldingly out of engagement with the screw thread while the reel is at rest and adapted when the reel is 120 rotating to be moved by the outward movement of said swing arm into engagement with the screw thread to cause the reel to move toward the wheel until the clutch members engage or from the wheel until the 125 clutch members are disengaged.

8. A trolley retriever, comprising a housing, a shaft journaled therein and provided with a screw thread, a wheel rigid on the shaft and provided with a clutch member, a 130

reel journaled on the shaft and provided with a companion clutch member, a swing arm pivoted to the reel, a disk rigid with the reel and provided with an opening extending from its periphery to the shaft, a dog occupying said opening and pivotally connected to the swing arm, and a spring bearing against said dog and secured to the swing arm and

adapted to hold the dog normally out of engagement with the screw thread.

In testimony whereof I affix my signature, in the presence of two witnesses.

MADISON F. HODGE.
